SELF OPENING DIE HEAD

Filed April 1, 1921

2 Sheets-Sheet 2

UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

SELF-OPENING DIE HEAD.

Application filed April 1, 1921. Serial No. 457,801.

To all whom it may concern:

Be it known that I, ALBERT FRANK BREITENSTEIN, a citizen of the United States, residing at New Haven, in the county of New Haven and State of Connecticut, have invented a new and useful Improvement in Self-Opening Die Heads; and I do hereby declare the following, when taken in connection with the accompanying drawings and

10 the characters of reference marked thereon, to be a full, clear, and exact description of the same, and which said drawings constitute part of this application, and represent, in—

15 Fig. 1 a perspective view of a self-opening die-head embodying my invention.

Fig. 2 a view thereof in front elevation.

Fig. 3 a view thereof in rear elevation.

Fig. 4 a view thereof in side elevation on a reduced scale.

20 Fig. 5 a view thereof in central longitudinal section on the line 5—5 of Fig. 2.

Fig. 6 a view thereof in transverse section on the line 6—6 of Fig. 5.

Fig. 7 a view corresponding to Fig. 5 but 25 showing the device tripped and the chasers in their open or retired positions.

Fig. 8 a detached view in elevation of the tripping-lever.

30 Fig. 9 a detailed, perspective view showing the engagement of the segment and bolt.

My invention relates to improved self-opening die-heads primarily designed for use in automatic screw-machines but not so limited, the object being to produce a compact, efficient and reliable tool constructed with special reference to its reduction in length, whereby it is particularly adapted for use in screw-machines wherein its reduction in length incidentally permits all of the 35 other tools used in the same turret with it to also be reduced in length.

With these ends in view, my invention consists in a self-opening die-head characterized by having the bolt-returning spring 45 of its tripping-mechanism mounted independently of the bolt thereof.

My invention further consists in a self-opening die-head having a single back-plate mounting the tripping-mechanism thereof 50 and serving to maintain the cam-ring in position upon the body of the die-head.

My invention further consists in certain details of construction and combination of

parts as will be hereinafter described and pointed out in the claims.

In carrying out my invention as herein shown, it is applied to a self-opening die-head of familiar construction, apart from my invention, which relates in particular to the tripping-mechanism, which performs both locking and tripping functions.

The four chasers 10 of the die-head are located in four radial slots 11, arranged quartering with respect to each other in the flat outer face 12 of the die-head body 13, which has a concentric bearing 14 mounting an oscillatory cam-ring 15, from the outer edge of which four eccentric segmental cam-lugs 16 project and enter transverse slots 17 formed in the inner edges of the respective chasers, whereby the same are radially operated by the oscillation of the ring. The inner edge of the said ring is formed with a rearwardly-opening, annular spring-chamber 18 which receives a bowed, helical spring 19, employed for automatically turning the ring in the direction of simultaneously opening or retiring the chasers. The said spring is interposed between a pin 20, projecting forwardly into the said chamber 80 from a back-plate 21, and a pin 22, projecting rearwardly into the chamber from the ring, the said back-plate constituting one of the features of my present invention. Of these two pins, the pin 20 constitutes the 85 point of purchase from which the spring acts through the pin 22 to rotate the cam-ring in the direction of opening the chasers. The rotary movement of the ring in the direction of opening, is limited by a stop-plunger 23, located in a threaded-bushing 24 mounted in the cam-ring and projecting from the periphery thereof, the said plunger having a stem 25 encircled by a spring 26 located within the bushing and having its 90 outer end threaded for the application of a head 27, by means of which the plunger may be manually retracted. The inner end of the said plunger normally projects into a segmental, peripheral slot 28 formed in the 100 bearing 14 aforesaid, and at one end intersecting an anvil 29 radially mounted in the said bearing and providing an abutment for the pin 23, which is brought to a bearing upon the anvil for stopping the rotation of 105 the cam-ring in the direction of opening.

When it is desired to rotate the cam-ring beyond the anvil, for the purpose of removing the chasers, the plunger 23 is retracted against the tension of its spring 26, by means of its head or finger-button 27.

The said cam-ring is held against rearward movement upon the bearing 14 by means of the back-plate 21, which engages with and covers its rear edge and confines the spring 19 in the spring-chamber 18, the back-plate 21 being mounted upon the concentric, reduced portion 30 of the body 13. The said plate 21, in my improved construction, discharges the three-fold function of mounting the tripping-mechanism, of holding the cam-ring in place, and of closing the spring-chamber in the inner face thereof, whereas, heretofore, an intermediate plate has been employed for holding the cam-ring in place and for closing the spring-chamber therein.

The said plate 21 is formed with a rearwardly-projecting integral hub 31, embraced by the bowed arms 32 of a tripping lever 33, the said arms being pivotally connected with the hub by means of trunnions 34. Screws 35, passing through the hub 31, enter the bearing 14 of the body 13 for rigidly securing the back-plate thereto. The said lever mounts a locking-member in the form of a bolt 36, secured in place by a pin 37 and projecting forward into the spring-chamber 18, in which it engages with the forward end 38 of a segment 39, located in the chamber and carrying a forwardly-projecting stud 40, connected with the cam-ring 15, by its interposition between two adjusting-screws 41 mounted therein, whereby, by adjusting them, the position of the segment with respect to the cam-ring is shifted and hence the position in which the ring is normally locked by the bolt 36 against the tension of the spring 19.

At its outer end the tripping-lever 33 is formed with a hole 43 for the passage transversely through it of a tripping-screw 44, mounting a nut 45 and locking-nut 46, the former being engaged with the face of the lever to tilt the same, as in Fig. 7. The said screw is itself pivotally mounted in a slotted-arm 47, offsetting from an integral circular flange 48 at the forward end of the hollow shank 49, by which the die-head is mounted in the usual manner in the turret of an automatic screw-machine.

Normally, the nut 45 is held away from the face of the tripping-lever by the action of a die-head-return spring 50, interposed between the head of a screw 51 entering the stem 52 of the body, and the bottom of a spring-chamber 53 in the end of the shank, the said spring 50 exerting a constant effort to draw the die-head bodily inward toward the integral flange 48 of the shank, this being its cutting position. When, however, at

the close of any given cutting operation, the die-head is pulled outward by the work away from the shank against the tension of the spring 50, the nut 45 is engaged by the face of the tripping-lever 33 and the same thrown into its inclined position (Fig. 7), in which the locking-bolt 36 is retracted from the spring-chamber 18 in the cam-ring 15 and disengaged from the forward end 38 of the segment 39, thus permitting the cam-spring 19 to act to rotate the cam-ring and thus automatically retire or open the chasers for the release of the work. The instant the chasers let go of the work, the said spring 50 asserts itself to return the die-head to its normal position. As the tripping-lever 33 rocks toward its locking-position, the end of the locking-bolt 36 engages with the rear face of the segment 39. The cam-ring 15 is now turned in the direction of closing the chasers against the tension of the spring 19, by means of a spring-finger 54 secured to its periphery by means of a screw 55 and two dowel-pins 56. This movement may be effected either manually or in the customary manner by an abutment upon the machine. As the cam-ring turns, the segment, carried by it, rides under, so to speak, the end of the said bolt 36. As soon as the ring reaches the limit of its rotation in the direction of closing, the bolt is entered into the spring-chamber 18, so as to stand in front of the end 38 of the segment, by means of a locking-bolt-return spring 57 bearing against the inner face of the back-plate 21, and encircling a plunger 58 loosely mounted in a depending extension 59 of the tripping-lever 33 (Fig. 8) and having its headed forward end extended into a recess 60 in the bearing 14 of the body 13, the opposite end of the said spring being seated against the headed inner end of the plunger 58. At its opposite end, the plunger 58 is provided with a threaded nut 61. For coupling the die-head, as a unitary structure, with the shank, by means of which it is mounted in the turret, I employ two coupling-pins 62 mounted in the flange 48 of the shank 49 and extending forward therefrom into holes 63 in the body 13, in the customary manner.

By mounting the locking-bolt return spring 57 of the tripping-lever independently of the locking-bolt 36, I am enabled to reduce the length of the bolt to the mere requirements of its co-action with the segment 39 of the cam-ring 15, whereas, in the self-opening die-heads of the prior art, the locking-bolt has been made sufficiently long to serve as a means for mounting its return-spring, necessitating the employment of a much longer die-head body than would otherwise be necessary and so resulting in the lengthwise extension of the whole die-head structure, and this, in turn, necessitat-

ing the employment of correspondingly long tools to be used in conjunction with it in the turrets of automatic screw machines.

By mounting the locking-bolt return spring independently of the locking-bolt, as upon a plunger, as herein shown and described, I am enabled to reduce the length of the die-head, as a tool, to the minimum, and, incidentally, to use but a single back-plate, serving not only for the mounting of the tripping-mechanism but also for the holding of the cam-ring in place upon the die-head body, whereby I eliminate the intermediate back-plate heretofore employed for holding the cam-ring in place.

I do not limit myself to the exact construction of the self-opening die-head herein shown and described, my invention being characterized by a self-opening die-head having the locking-bolt return-spring of its tripping-mechanism made independent of the locking-bolt thereof and further characterized by having its tripping-mechanism mounted upon and carried by a single back-plate also serving to hold the cam-ring in place upon the die-head body.

I claim:

1. A self-opening die-head having a body, chasers, a cam-ring, a cam-ring spring, a back-plate mounted upon the body and holding the cam-ring in place thereupon, and a pivotal tripping-mechanism carried by the back-plate and including a locking-bolt co-acting with the cam ring to hold the same in the closed position of the chasers against the tension of the cam-ring spring.

2. A self-opening die-head having a body, chasers, an oscillating cam-ring for the op-

eration of the chasers, a cam-ring spring, a single back-plate mounted upon the body and holding the cam-ring in place thereupon, and a tripping-mechanism carried by the said back-plate and including a tripping-lever pivotally connected therewith and mounting a locking-bolt co-acting with the cam-ring, and also mounting a plunger extending forward into the said body and carrying a spring for returning the locking-bolt into its locked relation to the cam-ring.

3. A self-opening die-head, having a body, chasers, an oscillating cam-ring for the operation of the chasers, a cam-ring spring for turning the cam in the direction of retiring the chasers, an adjustable segment connected with the cam-ring, a single back-plate mounted upon the said body, holding the cam-ring in place thereupon and confining the cam-spring in place therein; and a tripping-mechanism carried by the said back-plate and including a tripping-lever pivotally mounted thereupon, a locking-bolt carried by the said lever and co-acting with the said segment, and a plunger carried by the said lever at a point below the said bolt, extending forward into the said body and mounting a spring operating to re-engage the said bolt with the said segment after the operation of the tripping-mechanism.

In testimony whereof, I have signed this specification in the presence of two subscribing witnesses.

ALBERT F. BREITENSTEIN.
